[57] CLAIM

The ornamental design for a combined hog trough feeder and divider, as shown and described.

DESCRIPTION

FIG. 1 is a perspective view of a combined hog trough feeder and divider showing my new design;

FIG. 2 is a front elevational view thereof, the rear being substantially similar in appearance;

FIG. 3 is an end elevational view thereof, the opposite end being substantially similar in appearance;

FIG. 4 is a top plan view thereof; and

FIG. 5 is a bottom plan view thereof.
